APPARATUS FOR FORMING SPIRALLY WRAPPED PLASTIC STRIP FIBER

Frederick Slavek, New York, N. Y.

Application March 17, 1953, Serial No. 342,818

9 Claims. (Cl. 57—12)

This invention relates to fibers made of a thin strip of plastic materials, and is particularly directed to an apparatus for producing a plastic fibre which is formed by spirally wrapping a narrow strip of thin plastic material, such as cellophane, around a fine central thread, or around the strip itself.

The fibre is formed by spirally wrapping a thin strip of narrow plastic material, such as cellophane, around a central thread, the plastic strip being spiraled around the central thread in a plurality of layers, the individual spiral layers of plastic strip material overlapping one another to form a gripping binder between adjacent spiral bands. The central thread may be eliminated, the plastic strip being spirally wrapped around itself.

The conventional type of plastic wrapped fibre is formed by utilizing the conventional type of twisted thread, with a thin thread of cellophane or other plastic material wrapped around it.

This material has been found unsuited to many applications, due to the relatively dull finish of the material, and due to the tendency of the twisted threads to unravel when woven into a fabric or similar material.

The primary object of my invention is to provide an apparatus for producing a plastic fibre material, which is formed by spirally wrapping a plurality of layers of plastic strip material around a thin central thread.

An essential feature of the apparatus is the fact that it can be utilized with equal facility for producing fibres formed of thin plastic strip bands spirally wrapped around one another to form a plurality of spiral layers, or wrapped around a central reinforcing thread, such as a thin silk thread.

Another feature of the apparatus is the fact that it can be readily adjusted to produce a wide range of spiral pitches in the spacing of the adjacent spiral bands and layers of the plastic strip.

A further feature of the apparatus is that it can be utilized with equal facility to accommodate a wide range of widths and thicknesses of plastic strip materials, thus producing a wide range of fibre diameters and textures.

Another feature of the apparatus is the fact that the overlap between adjacent spiral bands around the fibre may be adjusted to vary the bond between adjacent spiral bands.

A further feature of the apparatus is the fact that the speed of the materials fed thereto, and the spiralling speed and feed may be varied to suit the type of fibre required, the degree of spiralling and the finished diameter and texture of the fibre.

Another object is to produce an apparatus which can be utilized with a wide range of plastic strip materials to produce a wide range of sizes and types of spirally wrapped plastic fibres.

The accompanying drawings, illustrative of one embodiment of my invention, together with the description of its construction and the method of operation and utilization thereof, as well as the plastic fibre produced thereby will

2

serve to clarify further objects and advantages of my invention.

In the drawings:

Fig. 1 represents a partial front elevation and a partial vertical section through the assembled apparatus, the tubular vertical drive shaft, the hub of the upper support bracket therefor and the central gear being shown in section, as shown by the broken line 1—1, shown in Fig. 2, the balance of Fig. 1, representing a front elevation of the apparatus, showing the means of feeding the plastic strip and the reinforcing thread to the apparatus, and the spiralling elements of the apparatus. The spinner yoke shown in Fig. 1 has been rotated through an angle of approximately 90° from the position shown in Fig. 2, in order to more clearly present the function thereof. A portion of the spinner yoke, rotated through an angle of about 180° from the position shown in Fig. 1, is shown by dot-dash line in Fig. 1.

Fig. 2 represents a right hand side elevation of the assembled apparatus, shown in Fig. 1, taken at 2—2, Fig. 1, showing the spool feeding the reinforcing thread and the roll feeding the plastic strip in their respective positions, relative to the feed rollers, also the method of spiralling and supporting the completed fibres.

Fig. 3 is a plan view of the apparatus, shown in Figs. 1 and 2, with the thread spool and the plastic strip roll removed to show the feed rollers which support the materials during the spiral wrapping operation, taken at 3—3, Fig. 2.

Fig. 4 is an enlarged schematic front elevation of the spirally wrapped plastic fibre produced by the apparatus, showing the relative position, spacing and overlap of the spiral bands of plastic strip used in forming it.

Fig. 5 is an enlarged schematic vertical section through the material shown in Fig. 4, showing the central reinforcing thread and the relative positions and overlap of the spiral bands and the multiple layers of spiral plastic strip used in forming it.

It will be understood that the following description of the spirally wrapped plastic fibre, and the description of the construction and the method of operation and utilization of the apparatus provided for producing it is intended as explanatory of the invention and not restrictive thereof.

In the drawings, the same reference numerals designate the same parts throughout the various views, except where otherwise indicated.

One embodiment of the apparatus, utilized to form the spirally wrapped plastic fibre is shown in Figs. 1 and 2. The apparatus is supported by a frame, comprising a pair of substantially vertical column members 10 and 11, which are in turn supported by a base 12, the operating mechanism being driven by a motor, or other suitable drive member (not shown), which drives a pulley 14 attached to a main drive shaft 15, rotatably supported by the vertical frame columns 10 and 11.

The plastic strip material 16, in the form of a narrow strip of thin cellophane, or similar plastic sheet material, is fed from a substantially cylindrical roll 17, mounted above the vertical frame members and angularly disposed thereto, the roll 17 being located substantially parallel to a pair of angularly mounted feed rollers 19 and 20, which are mounted at the top of the frame in a manner hereinafter described in greater detail. The plastic strip roll 17 is trunnioned on a cylindrical shaft 21 mounted above the frame.

A spool 22, feeding a fine silk thread 23, or a similar thread, which forms a reinforcement or center of the fibre, is rotatably supported above the frame, the spool being located in alignment with a tubular vertical drive shaft 25, which is located substantially parallel to and supported by the left hand vertical frame column 10, the

thread 23 being fed through the center of the tubular vertical shaft in the manner indicated in Fig. 1.

The hollow tubular shaft 25 is driven by a bevel gear 27, attached thereto, the bevel gear 27 meshing with a mating bevel pinion 28, which is mounted on one end of the main drive shaft 15.

A countershaft 30, located substantially parallel to the tubular vertical shaft, has a pair of spur pinions 31 and 32 attached to the upper and lower ends thereof, respectively, as indicated in Fig. 1. The upper spur pinion 31 is driven by a spur gear 33, attached to the upper end of the rotating tubular shaft 25, the lower spur pinion 32 meshing with the upper gear 34 of a pair of cluster gears, trunnioned on the tubular vertical shaft 25, the lower spur idler 35, integral with the upper cluster gear 34 meshing with and driving a spinner pulley drive gear 36, which is attached to the upper end of a spinner pulley drive shaft 37, located substantially parallel to the tubular vertical shaft 25, in substantial alignment with the lower end thereof.

The upper and lower support members 39 and 40 of a bearing bracket, the hub of each of which surrounds the tubular vertical shaft, support the parallel countershaft 30, on which the spur pinions 31 and 32 are mounted, a bushing 42, fitted to the hub of each of the bracket support members supporting the outer circumference of the tubular vertical shaft 25. A vertical connecting member 41, integral with the bearing bracket support members 39 and 40, is attached to the left-hand column 10 of the frame.

The countershaft 30 is trunnioned in the outer ends of the arms 44 and 45 of the bearing support members 39 and 40, respectively, the arms 44 and 45 being integral with the hubs of the bearing support members respectively, and substantially perpendicular to the hub axis thereof.

A substantially L-shaped spinner yoke 46, the central hub 47 of which is attached to the lower end of the tubular vertical shaft 25, is mounted at the bottom of the vertical shaft, below the cluster gears 34 and 35.

An auxiliary boss 48, parallel to the central hub 47, integral with the horizontal arm 49 of the spinner yoke, is located opposite a substantially vertical arm 50 depending from and substantially perpendicular to the horizontal arm of the spinner support yoke 46.

The spinner pulley drive shaft 37, to the upper end of which the spinner pulley drive gear 36 is attached, is trunnioned in the auxiliary boss 48 of the spinner yoke 46, a spinner pulley 52, the rim 53 of which is of concave arcate contour, being attached to the bottom of the spinner pulley drive shaft, below the horizontal arm 49 of the spinner yoke, in the manner indicated in Figs. 1 and 2.

The spirally wound fibre 54, shown in detail in Figs. 4 and 5, and hereinafter described in greater detail, is fed from the bottom of the tubular shaft to a spool 55, trunnioned on a shaft 56 attached to the base 12 of the frame, in a manner hereinafter described in greater detail.

A pair of feed rollers 19 and 20, individually trunnioned on a pair of parallel shafts 60 and 61, and mounted at the outer end of the side arms 62 and 62a of a substantially U-shaped yoke, adjustably supported at the top of the upper frame cross-member 63, is provided to guide and feed the plastic strip 16 and the silk thread 23 from the roll 17 and the spool 22, respectively, to the hollow center of the tubular vertical shaft 25.

The angular position of the feed rollers 19 and 20 and that of the tape roll parallel thereto, are adjusted so that angle of approach of the plastic strip 16, relative to the vertical shaft axis, is determined by the spiral angle of the strip, wrapped around the central reinforcing thread.

The U-shaped yoke is supported by a tubular member 64, which is attached to the upper frame cross-member by a pair of pillow blocks 65 and 65a, the tubular member 64 rotatably supporting a roller drive shaft 66, fitted to the center thereof.

A stepped cone pulley 67, attached to one end of the roller drive shaft 66, is driven by an oppositely tapered stepped cone pulley 68, attached to the outer end of the main drive shaft 15, by a belt 69, of circular cross-section, V-form, or other suitable cross-section, conforming to the convolutions in the cone pulleys 67 and 68, the speed of the roller drive pulley being varied by the position of the belt relative to the pulleys, thus obtaining a wide range of pulley ratios.

A bevel pinion 70, attached to the inner end of the roller drive shaft 66, meshes with a mating bevel gear 71, attached to a rotating intermediate roller drive shaft 72, trunnioned in the side arms 62 and 62a of the yoke, the bevel gear intermediate shaft being substantially parallel to the roller support shafts 60 and 61, and located a predetermined distance from the fixed roller support shaft 61, the ends of which are attached to the outer ends of the side arms 62 and 62a of the yoke, the ends of the shaft being held in place by set screws, or other suitable locking means.

A spur pinion 73 attached to the intermediate roller drive shaft 72, adjacent the left hand side arm 62 of the yoke, drives a spur gear 74, attached to the adjacent end of the lower feed roller 20, which is trunnioned on the lower feed roller shaft 61, the fixed feed roller shaft 61 being attached to the outer ends of the side arms 62 and 62a of the yoke, a set screw or other locking means being inserted in the yoke arms in the manner indicated in Fig. 3.

30 A pair of angularly adjustable roller support arms 76 and 76a is attached to the outer ends of the fixed feed roller shaft 61, the roller support arms being located outside and substantially parallel to the yoke side arms 62 and 62a. The end of each roller support arm 76 and 76a, attached to the fixed feed roller shaft 61 has a slot 77 therethrough, a lock screw 78 inserted through the upper segment of the arm and threadably fitted to the lower segment thereof, clamping the arm segments, adjacent the slot 77, to the roller support shaft 61.

35 A pair of sliding blocks 80, each of which is slidably fitted within a channel 81 cut through the center of the outer portion of each roller support arm, adjustably supports the ends of the adjustable roller support shaft 60, each end of the shaft being inserted through an opening in the adjacent block, each sliding block being attached to the shaft by a set screw or other suitable attaching means.

40 An adjusting screw 82, threadably inserted in the outer end of each roller support arm, beyond the channel 81, is provided in each arm, the lower end of the screw being attached to the adjacent sliding block 80 to adjust the position of the block, relative to the roller support arm, thereby adjusting the position of the adjustable roller support shaft 60, relative to the fixed roller support shaft 61, and in that manner adjusting the spacing between the feed rollers 19 and 20, and adjusting the pressure of the feed rollers against the plastic strip 16, fed therebetween. A lock nut 83 is threadably fitted to each adjusting screw 82, to lock the adjusting screw in the adjusted position, thereby retaining the block 80 in its adjusted position and maintaining the required spacing between the feed rollers.

45 The spur gear 74 meshes with a similar spur gear 85, attached to the adjacent end of the upper feed roller 19, which is trunnioned on the adjustable feed roller shaft 60, to drive the upper feed roller 19.

50 In this manner, the two feed rollers are tiltable relative to the frame, by adjusting the angular position of the U-shaped yoke. The angular axial relation of the upper or adjustable feed roller, relative to the lower feed roller in a plane perpendicular to the longitudinal roller axis, is 55 adjustable by angularly tilting the roller support arms 76 and 76a about the fixed roller support shaft 61, the spacing between the rollers being adjusted by moving the sliding blocks 80 in the manner hereinbefore described.

60 75 As indicated in Fig. 1, the plastic strip roll 17 is located

above the feed rollers 19 and 20 in a position substantially parallel to the feed roller 19 and 20, to enable the plastic strip 16 to be fed between the feed rollers in a direction substantially perpendicular to the longitudinal axis thereof.

A circumferential groove 87, of substantially rectangular cross-section, is cut around the outer circumference of the outer feed roller 19.

The plastic strip 16 is fed between the feed rollers 19 and 20 in a position substantially parallel to one edge of the circumferential groove 87, the strip being guided along a direction substantially perpendicular to the longitudinal axis of the rollers 19 and 20. The angular positions of the feed rollers 19 and 20 and the strip roll 17, substantially parallel thereto, are adjusted so that the strip approaches the central reinforcing thread 23 at an angle required to form the spiral angle of the strip around the central thread 23.

The position of the feed rollers 19 and 20, relative to the tubular vertical shaft 25, is such that the strip is directed from the rollers toward the center of the tubular vertical shaft 25. The fine reinforcing thread 23, fed from a spool 22 located above the rollers 19 and 20, is directed toward the groove 87 in the center of the upper feed roller 19, through an opening in the head of a guide 88, which is attached to the top of the left-hand vertical column 10 of the frame, the guide head being located in substantial alignment with the center of the tubular vertical shaft 25, in order to feed the reinforcing thread toward the center of the vertical shaft, the angular direction of the plastic strip 16, relative to the shaft, being such that the plastic strip joins the reinforcing thread at a point above the top of the tubular vertical shaft 25, in substantial alignment with the center of the passage therethrough, so that the plastic strip 16 and the reinforcing thread 23 are fed simultaneously through the central passage in the tubular vertical shaft 25, the strip 16 being spirally wrapped around the central thread in a manner hereinafter described in greater detail, to form the completed fibre, shown in Figs 4 and 5.

The angle formed by the feed rolls 19 and 20, relative to the vertical shaft, is so adjusted that the plastic strip 16 approaches the central thread 23 at an angle corresponding to the spiral angle of the strip relative to the longitudinal fibre axis.

When the spirally wrapped fibre 54 leaves the bottom of the tubular vertical shaft 25, it is guided by a guide roller 89, trunnioned on a shaft attached to a bracket 90, attached to or integral with the horizontal arm of the spinner yoke, the fibre being wrapped two or more turns around the spinner pulley to tension the fibre around the circumference of the spinner pulley.

From the opposite side of the spinner pulley 52, the fibre is guided by an upper roller 91 and a lower roller 92, trunnioned on shafts attached to the vertical arm 50 of the spinner yoke, toward the collecting spool 55, mounted on a vertical shaft 56, attached to the base 12 of the frame, around which it is wound by the rotation of the spinner yoke.

The operation of the apparatus is substantially as follows:

The plastic strip 16, which is fed from the strip roll 17 between the feed rollers 19 and 20, toward the passage through the center of the tubular shaft 25, is gripped between the feed rollers 19 and 20.

The reinforcing thread 23 is fed from the spool 22, through the groove 87 in the upper feed roller 19 to the passage in the center of the tubular vertical shaft 25, the reinforcing thread being directed toward the shaft passage.

The rotation of the spinner yoke 46, at the bottom of the tubular shaft, spirally wraps the plastic strip 16 around the central reinforcing thread 23, an overlap 93 being formed between adjacent spiral bands 94 of the plastic strip 16 as it is wound.

The spiral angle formed by individual bands of strip

material around the central thread, and the overlap between adjacent strips is determined to a large extent, by the angular position of the axes of the feed rollers 19 and 20 relative to the vertical shaft, which determines the angle of approach of the plastic strip relative to the vertical axis of the tubular shaft 25, through which the materials are fed.

The number of turns of completed fibre wrapped around the spinner pulley rim 53 tensions the fibre so that uniform tension is provided between the feed rollers 19 and 20 at the top of the frame, which grip the plastic strip, and the spinner pulley 52 below the bottom of the tubular shaft 25, which holds the completed fibre.

The lead of the spiral bands of spirally wrapped plastic strip around the central reinforcing thread is determined by the angle of approach of the plastic strip 16 relative to the vertical shaft axis, coupled with the relation between the rotational rate of the spinner yoke 46 and the rate at which the plastic strip 16 is fed from the roll 17, which is determined by the rate at which the completed spirally wound fibre is drawn through the tubular vertical shaft by the spinner pulley.

Where the feed rate of the finished, spirally wound fibre is increased, relative to the rate of rotation of the horizontal arm 49 of the spinner yoke, the number of layers of spirally wrapped strip around the reinforcing thread 23 is increased, thus increasing the diameter of the completed fibre.

The pressure exerted on the overlapping area 93 of the spirally wrapped plastic strip bands 94, during the winding process, caused by the tension on the plastic strip during the winding thereof, coupled with the inherent characteristics of the plastic strip material, such as cellophane, forms a bond between the overlapping area of the outer spiral band and the adjacent band of the strip material, thus providing a relatively tight spirally wound fibre, which will not unravel under normal operating conditions and normal usage.

By maintaining a relatively uniform tension on the plastic strip 16, obtained by adjusting the tension between the feed rollers 19 and 20 and by maintaining a relatively uniform rate of rotation of the spinner yoke and the spinner pulley, mounted thereon, a spirally wound fibre of uniform diameter and relatively uniform spiral lead is obtained, the diameter and lead being varied by varying the tension between the feed rollers and adjusting the rate of rotation of the spinner yoke 46 by means of the stepped cone pulleys 67 and 68.

The guide roller 89 located at the center of the bottom of the tubular vertical shaft 25, and the location of the feed rollers, relative to the top of the vertical shaft 25, maintain the spirally wound fibre at the bottom of the vertical shaft in substantial axial alignment with the plastic strip 16 and the reinforcing thread at the top of the vertical shaft 25, so that the rate of spiralling and the lead between adjacent spiral bands is maintained relatively uniform.

The reinforcing thread 23 at the center of the spirally wound fibre may be eliminated, the plastic strip being wrapped around itself in substantially the same manner. A somewhat more uniform exterior surface of the spirally wound fibre is obtained by utilizing a central reinforcing thread 23, of the type employed.

The diameter of the finished spirally wound fibre may be varied by varying the diameter of the reinforcing thread 23, and varying the thickness or width of the plastic strip fed toward the apparatus.

The lead of the spirally wrapped bands and the overlap between adjacent spiral bands may be varied by varying the width of the plastic strip 16 in conformity with the finished diameter of the spirally wound fibre required, and the spiral lead required.

The number of layers of plastic strip forming the spirally wrapped fibre may be varied by adjusting the rotational speed of the spinner yoke, and varying the rate of

feeding the strip and the reinforcing thread to the tubular vertical shaft passage.

The outside diameter of the fibre may therefore be varied by varying the number of layers of spirally wrapped strip bands, forming the fibre, varying the thickness of the plastic strip, varying the width of the plastic strip and otherwise adjusting the lead between adjacent bands of plastic strip.

The method of supporting and driving the tubular vertical shaft may be altered considerably, the essentials of the construction and operation thereof remaining the same.

The method of supporting and adjusting the spacing between the feed rollers may be altered considerably, the primary feature being the adjustment of the spacing and pressure between the feed rollers in feeding the plastic strip to the vertical shaft passage.

The method of supporting the feed rollers above the frame, and the method of adjusting the angular relation between the feed rollers, relative to the tubular vertical shaft may be altered considerably, the essential features of the operation of the feed rollers remaining the same as hereinbefore described.

The method of supporting the spinner yoke and the spinner pulley, and the method of driving the spinner pulley may be altered, or varied considerably, the essential features of the operation of the spinner yoke and spinner pulley, that of spirally wrapping the plastic strip around the central thread to form the finished fibre remaining essentially the same.

The width and thickness of the plastic strip fed to the vertical shaft passage may be varied considerably, depending upon the material of which the plastic strip is made and the diameter and texture of the finished fibre required for a particular application.

The ratio of the speed of rotation of the feed rollers, relative to the spinner yoke and the spinner pulley may be varied considerably by altering the ratios between the various gears in the drive gear trains used, the ratio adopted depending upon the width of the plastic strip used and the number of layers of spirally wrapped plastic strip utilized to form the finished fibre.

The method of transferring the finished fibre from the tubular vertical shaft to the collecting spool may be altered considerably, on condition that suitable gripping means is provided to grip and support the finished fibre during the spiral wrapping operation.

Instead of a single strip of plastic strip material, fed from a single roll, as shown in the drawings and hereinbefore described, a plurality of plastic strips may be utilized to form a plurality of layers of spirally wrapped plastic strip, forming the spiral wrappings of the completed fibre, the feeding angles of the individual strips, and the angle of approach of each strip to the vertical shaft passage being adjusted to provide the selected spiral angle and spiral lead of the finished fibre.

Where multiple plastic strips are used, a plurality of sets of feed rollers, individually adjustable for tension may be provided, the angular relation between the individual sets of feed rollers and the tubular vertical shaft being adjustable to provide the proper spiral angle and lead for each individual plastic strip in the multiple strip unit to provide a properly co-ordinated homogeneous multiple layer spirally wound fibre.

The cone pulleys driving the tubular vertical shaft and the feed rollers may be altered considerably, or replaced by other suitable drive means, provided adequate provision is made for adjusting and maintaining the ratio between the rotational speed of the feed rollers and the speed of the tubular vertical shaft, and the spinner yoke.

It will be apparent to one skilled in the art that applicant's principles may be applied in many modified forms beyond those illustrated and described herein, and therefore the following claims should not be limited to the forms illustrated but be deemed to apply to all equivalents as well.

What I claim is:

1. An apparatus for forming a fibre consisting of a central thread, with a thin plastic strip spirally wrapped around the central thread, comprising a frame, a tubular, substantially vertical shaft having a central passage therethrough rotatably supported by the frame, a pair of cylindrical rotatable feed rollers supported by said frame, means for supplying a thin narrow plastic strip toward the feed rollers, means for feeding a fine central thread toward the tubular shaft passage, said feed rollers being angularly adjustable relative to the tubular shaft axis, one of said feed rollers being movable relative to the other to adjust the gripping pressure between the feed rollers against the plastic strip fed therebetween, the feed rollers being positioned to angularly direct the plastic strip toward the tubular shaft passage, co-ordinated with the plastic strip spiral angle, means attached to the end of the tubular shaft, opposite the feed rollers, for rotating the plastic strip within the tubular shaft passage to progressively spirally wrap the plastic strip around the central thread, with an overlap between adjacent spiral strip elements, a rotatable fibre retaining member supported by said plastic strip rotating means, said fibre retaining member being operative to progressively retain sections of the spirally wrapped fibre during the spiral wrapping process, means co-ordinating the rotational speed of the plastic strip feed rollers with the tubular shaft rotation, and means co-ordinating the rotation of the spirally wrapped fibre retaining means at the opposite end of the tubular shaft with the plastic strip feed roller rotation to form a uniformly spaced spirally wrapped fibre.

2. An apparatus for forming a fibre consisting of a central thread, with a thin plastic strip spirally wrapped around the central thread, comprising a frame, a tubular shaft having a central passage therethrough rotatably supported by the frame, a pair of cylindrical rotatable feed rollers supported by said frame, means for supplying a thin, narrow plastic strip to the feed rollers, means for feeding a fine central thread to the tubular shaft passage, said feed rollers being angularly adjustable relative to the tubular shaft axis, one of said feed rollers being movable relative to the other to adjust the gripping pressure between the feed rollers against the plastic strip fed therebetween, the feed rollers being positioned to angularly direct the plastic strip toward the tubular shaft passage, co-ordinated with the plastic strip spiral angle, a spinner yoke attached to the end of the tubular shaft opposite the feed rollers, a spinner pulley rotatably supported by the spinner yoke, said spinner pulley being substantially parallel to the tubular vertical shaft and located a short distance therefrom, the spirally wrapped plastic strip fibre being progressively wound around the spinner pulley to retain the fibre fed from the vertical shaft passage, the rotation of the spinner yoke being co-ordinated with the feed rollers rotation to form a spirally wrapped fibre with an overlap between adjacent spiral strip elements, and means co-ordinating the rotational speed of the spinner pulley relative to the plastic strip feed rollers rotation to form a uniformly spaced, spirally wrapped fibre.

3. An apparatus for forming a fibre consisting of a central thread, with a thin plastic strip spirally wrapped around the central thread, comprising a frame, a tubular vertical shaft having a central passage therethrough rotatably supported by the frame, means driving said tubular shaft, a pair of substantially cylindrical feed rollers mounted in close proximity to the tubular shaft, angularly adjustable means pivotally attached to the frame rotatably supporting said feed rollers, one of said feed rollers being fixed in position relative to the angularly adjustable roller support means, means fitted to said angularly adjustable feed roller support means for adjusting the position of the second feed roller relative to the fixed position feed roller, means for supplying a thin narrow strip of plastic material toward the feed rollers, means for moving the adjustable feed roller relative to the fixed feed roller to

adjust the circumferential spacing between the feed rollers, the adjustable feed roller having a groove around the outer circumference thereof, means feeding a fine central thread through the feed roller groove toward the tubular shaft passage, a spinner yoke attached to the end of the tubular shaft opposite the feed rollers, a spinner pulley rotatably supported by the spinner yoke, said spinner pulley being substantially parallel to the tubular vertical shaft and located a short distance therefrom, the spirally wrapped fibre being wound around the spinner pulley to restrain the fibre fed from the tubular shaft passage during the spiral wrapping process, a fibre receiving spool rotatably supported by the frame, the fibre receiving spool being in substantial alignment with the tubular shaft longitudinal axis, means attached to the spinner yoke operative to wind the spirally wrapped fibre, delivered from the spinner pulley, around the fibre receiving spool, the rotation of the spinner yoke being co-ordinated with the strip feed rollers speed and angle to spirally wrap the plastic strip around the central thread, means co-ordinating the rotational speed of the feed rollers relative to the tubular shaft, and means co-ordinating the rotational speed of the spinner pulley relative to the feed rollers rotation to form a uniformly spaced spirally wrapped fibre.

4. An apparatus for forming a plastic fibre consisting of a thin plastic strip spirally wrapped around the longitudinal fibre axis, comprising a frame, a tubular vertical shaft having a central passage therethrough rotatably supported by the frame, a pair of cylindrical, rotatable feed rollers supported by the frame, means feeding a thin narrow plastic strip toward the feed rollers, the feed rollers being angularly adjustable relative to the tubular shaft axis, one of said feed rollers being movable relative to the other to adjust the circumferential gripping pressure between the feed rollers against the plastic strip fed therebetween, means attached to the end of the tubular shaft, opposite the feed rollers, for rotating the plastic strip within the tubular shaft passage to progressively spirally wrap the plastic strip around the longitudinal fibre axis, with an overlap between adjacent spiral strip elements, a spinner pulley rotatably supported by the plastic strip rotating means, said spinner pulley being substantially parallel to the vertical shaft axis, and located a short distance therefrom, the spirally wrapped fibre being wound around the spinner pulley to restrain the fibre during the spiral wrapping process, means supported by the frame for receiving the spiral wrapped fibre fed from the spinner pulley, and means supported by said plastic strip rotating means operative to guide the spirally wound fibre from the spinner pulley and simultaneously wind the spirally wrapped fibre around the fibre receiving means, means co-ordinating the rotation of the plastic strip rotating means with the plastic strip feed rollers speed and angle, and means co-ordinating the rotational speed of the spinner pulley relative to the feed rollers rotation to form a uniformly spaced spirally wrapped fibre.

5. An apparatus for forming a fibre consisting of a thin plastic strip spirally wrapped around the longitudinal fibre axis, comprising a frame, a tubular shaft having a central passage therethrough rotatably supported by the frame, a substantially U-shaped yoke pivotally supported by the frame, a feed roller rotatably supported by said yoke in a relatively fixed position, a cylindrical projecting shaft rotatably supporting the fixed feed roller fitted to said yoke, a pair of angularly adjustable roller support arms attached to the fixed feed roller shaft, a second feed roller rotatably supported by the roller support arms substantially parallel to the fixed feed roller, the second feed roller having a cylindrical projecting shaft extending beyond the ends thereof, means slidably supported by the roller support arms slidably supporting the second feed roller support shaft, an adjusting screw threadably fitted to each of said roller support arms operative to move the cylindrical support shaft of the second feed roller rela-

tive to the fixed feed roller support shaft to adjust the circumferential spacing between the feed rollers, means for feeding a narrow plastic strip toward the feed rollers, said feed rollers being operative to grip the plastic strip and feed the plastic strip at an angle to the tubular shaft axis, means mounted adjacent the end of the tubular shaft, opposite the feed rollers operative to rotate the plastic strip within the tubular shaft passage to form a spirally wrapped fibre, with an overlap between adjacent plastic strip spiral elements, a spinner pulley rotatably supported by the plastic strip rotating means, said spinner pulley being substantially parallel to the tubular shaft axis, the spirally wrapped fibre being wrapped around the spinner pulley to restrain the spirally wrapped plastic fibre during the spiral wrapping process, means co-ordinating the rotational speed of the feed rollers with the tubular shaft rotation, and means co-ordinating the rotation of the spinner pulley at the opposite end of the tubular shaft with the feed rollers rotation.

6. An apparatus for forming a plastic fibre, consisting of a thin plastic strip spirally wrapped around the longitudinal fibre axis, comprising a frame, a tubular vertical shaft having a central passage therethrough rotatably supported by the frame, a pair of cylindrical, rotatable feed rollers mounted near the tubular shaft, means feeding a thin narrow plastic strip toward the feed rollers, a pair of cylindrical shafts rotatably supporting the feed rollers, a substantially U-shaped yoke pivotally supported by the frame supporting one of said feed roller shafts in a relatively fixed position, a pair of angularly adjustable roller support arms attached to the fixed feed roller shaft, means slidably supported by the roller support arms adjustably supporting the second feed roller support shaft, means fitted to said feed roller support arms for moving the movable feed roller support shaft relative to the fixed feed roller shaft to adjust the circumferential spacing between the feed rollers, means attached to the end of the tubular shaft, opposite the feed rollers, for rotating the plastic strip within the tubular shaft passage to progressively spirally wrap the plastic strip around the longitudinal fibre axis, with an overlap between adjacent spiral strip elements, a spinner pulley rotatably supported by the plastic strip rotating means, said spinner pulley being substantially parallel to the vertical shaft axis and located a short distance therefrom, the spirally wrapped fibre being wound around the spinner pulley to restrain the fibre during the spiral wrapping process, means supported by the frame for receiving the spirally wrapped fibre from the spinner pulley, and means rotatably supported by the plastic strip rotating means operative to simultaneously guide the spirally wrapped fibre from the spinner pulley and wind the fibre around the fibre receiving means, means co-ordinating the rotation of the plastic strip rotating means with the plastic strip feed rollers speed and angle, means co-ordinating the rotational speed of the feed rollers relative to the tubular shaft, and means co-ordinating the rotational speed of the spinner pulley relative to the feed rollers' rotation.

7. An apparatus for forming a fibre consisting of a central thread, with a thin plastic strip spirally wrapped around the central thread, comprising a frame, a tubular shaft having a central passage therethrough rotatably supported by the frame, a pair of cylindrical, rotatable feed rollers mounted near the tubular vertical shaft, one of said feed rollers having a circumferential groove, therearound, means for supplying a thin, narrow plastic strip toward the feed rollers, a pair of cylindrical shafts rotatably supporting the feed rollers, a substantially U-shaped yoke pivotally supported by the frame supporting one of said feed roller shafts in a relatively fixed position, a pair of angularly adjustable roller support arms attached to the fixed feed roller shaft, each of said roller support arms having a parallel faced slot therethrough, a pair of blocks slidably fitted to the roller support arm slots supporting

11

the movable feed roller shaft, means for moving said blocks relative to the fixed feed roller shaft to adjust the circumferential spacing between the feed rollers, the feed rollers being positioned to angularly direct the plastic strip toward the tubular shaft passage, co-ordinated with the plastic strip spiral angle, means for feeding a fine central thread through the feed roller groove toward the tubular shaft passage, means attached to the end of the tubular shaft opposite the feed rollers, for rotating the plastic strip within the tubular shaft passage to progressively spirally wrap the plastic strip around the central thread, with an overlap between adjacent spiral strip elements, a rotatable fibre retaining pulley supported by said plastic strip rotating means, the spirally wrapped fibre being wound around said fibre retaining pulley to progressively retain sections of the fibre during the spiral wrapping process, means co-ordinating the rotational speed of the strip feed rollers with the tubular shaft rotation, and means co-ordinating the fibre retaining means at the opposite end of the tubular shaft with the feed rollers.

8. An apparatus for forming a fibre consisting of a central thread, with a thin plastic strip spirally wrapped around the central thread, comprising a frame, a tubular vertical shaft having a central passage therethrough rotatably supported by the frame, means driving said tubular shaft, a pair of substantially cylindrical feed rollers mounted in close proximity to the tubular shaft, angularly adjustable means pivotally attached to the frame rotatably supporting said feed rollers, said angularly adjustable roller support means retaining one of said feed rollers in a relatively fixed position, means for adjusting the angular relation of the second of said feed rollers toward the relatively fixed roller, in a plane perpendicular to the longitudinal roller axes, means for supplying a thin narrow strip of plastic material toward the feed rollers, means for feeding a fine central thread toward the tubular shaft passage, means for moving the adjustable feed roller relative to the fixed feed roller to adjust the circumferential spacing between the feed rollers, a spinner yoke attached to the end of the tubular shaft opposite the feed rollers, a spinner pulley rotatably supported by the spinner yoke, said spinner pulley being substantially parallel to the tubular vertical shaft and located a short distance therefrom, the spirally wrapped fibre being wound around the spinner pulley to restrain the fibre fed from the tubular shaft passage, during the spiral wrapping process, a fibre receiving spool rotatably supported by the frame, substantially parallel to the tubular shaft axis, said spinner yoke having a depending arm substantially parallel to the fibre receiving spool axis, opposite the spinner pulley, the depending arm having a plurality of guide members rotatably fitted thereto to receive the spirally wrapped

fibre from the spinner pulley and wind the fibre around the fibre receiving spool, the rotation of the spinner yoke being co-ordinated with the strip feed rollers speed and angle to form a spirally wrapped fibre with an overlap between adjacent spiral strip elements, and means co-ordinating the rotational speed of the spinner pulley relative to the feed rollers rotation.

9. An apparatus for forming a plastic fibre consisting of a thin plastic strip spirally wrapped around the longitudinal fibre axis, comprising a frame, a tubular vertical shaft having a central passage therethrough rotatably supported by the frame, a pair of cylindrical, rotatable feed rollers supported by the frame, means feeding a thin narrow plastic strip toward the feed rollers, the feed rollers being angularly adjustable relative to the tubular shaft axis, one of said feed rollers being movable relative to the other to adjust the circumferential gripping pressure between the feed rollers against the plastic strip fed therebetween, a spinner yoke attached to the end of the tubular shaft, opposite the feed rollers, for rotating the plastic strip within the tubular shaft passage to progressively spirally wrap the plastic strip around the longitudinal fibre axis, with an overlap between adjacent spiral strip elements, a spinner pulley rotatably supported by the spinner yoke, said spinner pulley being substantially parallel to the vertical shaft axis and located a short distance therefrom, a guide pulley rotatably supported by the spinner yoke for directing the fibre from the tubular shaft passage to the spinner pulley, the spirally wrapped fibre being wound around the spinner pulley to restrain the fibre during the spiral wrapping process, means supported by the frame for receiving the spiral wrapped fibre from the spinner pulley, said spinner yoke having a depending arm substantially parallel to the fibre receiving means, opposite the spinner pulley, the depending arm having a plurality of guide members rotatably fitted thereto to receive the spirally wrapped fibre from the spinner pulley and wind the fibre around the fibre receiving means, means co-ordinating the rotation of the spinner yoke with the plastic strip feed rollers' speed and angle, and means co-ordinating the rotational speed of the spinner pulley relative to the feed rollers' rotation.
